UNITED STATES PATENT OFFICE.

CHARLES F. PFLANZE, OF ST. LOUIS, MISSOURI, ASSIGNOR OF ONE-HALF TO DENNIS J. GALVIN, OF ST. LOUIS, MISSOURI.

DIE.

1,202,311.

Specification of Letters Patent.

Patented Oct. 24, 1916.

Application filed February 17, 1915. Serial No. 8,722.

To all whom it may concern:

Be it known that I, CHARLES F. PFLANZE, a citizen of the United States of America, a resident of the city of St. Louis, State of Missouri, have invented certain new and useful Improvements in Dies, of which the following is a full, clear, and exact description, reference being had to the accompanying drawings, forming a part of this specification.

My invention relates to a die particularly adapted for use in cutting sheets of paper to produce envelop blanks.

One of the objects of the invention is to produce a cutting die which may be easily and quickly adjusted to cut envelop blanks, or other articles, of different dimensions.

Another object is to provide an efficient means for accurately truing the cutting elements, and this is preferably accomplished by bending a portion of the die structure to adjust the cutters with respect to each other.

In the manufacture of envelops a high degree of accuracy is required in forming the blank sheets, for if the blanks do not conform precisely to the desired configuration, the envelops will not be of the desired symmetrical form. It has been found in practice that the adjustable die structures heretofore employed in cutting envelop blanks, are frequently bent so that the cutters are displaced from their predetermined positions. Another undesirable feature of such die structures is the difficulty in constructing and assembling the different elements to produce a die of the desired accuracy. The main difficulty lies in locating and maintaining the corners of the cutters in certain relative positions, wherein they will form the corners of a true rectangular figure. This rectangular figure is the shape of the envelop, and if the corners of the angular cutters are not located in their proper positions, the envelop will not be a true rectangle.

In accordance with the preferred form of my invention, the cutters are connected to each other by means of a yieldable frame, and a bending device is associated with this frame. The bending device may be readily adjusted to bend the yieldable frame, thereby accurately adjusting the cutters to precise relative positions, wherein their corners will form the corners of a true rectangular figure.

Figure I is a top or plan view of a die embodying the features of my invention. Fig. II is a side elevation. Fig. III is an enlarged horizontal section, taken approximately on the line III—III, Fig. II.

A and B designate cutters arranged to form two pairs of cutting elements, the cutters A constituting one pair and the cutters B constituting the other pair. The cutters are preferably angular blades, arranged at an angle to each other and sharpened at their lower edges. The dotted lines 1 and 2 represent the outer edges of the closure flaps of an envelop blank, and the dotted lines 3 are imaginary lines showing the shape of the envelop as it appears when the flaps are folded. The cutters are provided with corners 4 which lie at the corners of the rectangular figure produced by the dotted lines 3.

The structure about to be described includes a connecting device, means for adjustably securing the cutters to said connecting device, and a truing device for bending the connecting device so as to positively locate the corners 4 at the corners of the rectangular figure produced by the dotted lines 3. The cutters of each pair may be adjusted toward and away from each other, and each pair of cutters may be adjusted toward and away from the other pair.

The means for connecting the cutters comprises a main rod 5, cross-shaped coupling members C slidably fitted to said main rod, and branch rods 6 firmly secured to said coupling members by means of pins 7. The branch rods 6 terminate in the coupling members C, but the main rod 5 passes entirely through said coupling member at points between the ends of the branch rods 6.

E designates split sleeves firmly secured to the cutters by means of nuts 9, each of said sleeves being provided with an abutment which engages the outer face of a cutter and a screw threaded end 10 for the reception of the nut 9. The slots 11 formed in the split sleeves extend from the outer ends of said sleeves and terminate at apertures 12. The sleeves E are slidably fitted to the rods 6, and their free outer ends may be contracted to firmly engage said rods, thereby firmly securing the cutters to the rods.

13 designates nuts screwed onto the outer

ends of the sleeves E, and provided with inclined abutment faces 14 adapted to engage the yieldable ends of said sleeves, as shown in Fig. III. The end faces of the yieldable sleeves are preferably inclined, or slightly curved, at the points where they engage the abutment faces 14, so that the pressure exerted by tightening the nuts 13 will positively and firmly force the yieldable ends of the sleeves into engagement with the rods 6. It will be noted that the cutters may be easily and quickly adjusted on the rods 6, by simply unscrewing the nuts 14, sliding the sleeves E along the rods 6, and then tightening the nuts 14 to secure the cutters in the desired positions.

Each coupling member C is provided with a split sleeve E', similar to the sleeves E, and a nut 13', adapted to contract the yieldable end of said split sleeve, so as to secure said coupling member C to the rod 5. Each pair of cutters may be adjusted toward and away from the other pair by unscrewing one of the nuts 13' to release a coupling member C from the rod 5, then sliding said coupling member along the rod 5, and thereafter tightening the nut 13' to secure the coupling member.

In using the die it is placed upon the pile 30 of sheets to be cut, and then forced downwardly by pressure applied to the top faces of the cutters. It is somewhat difficult to obtain absolutely straight rods 5, and they are frequently bent in handling the dies. 35 The parts are so constructed that if the rod 5 is not perfectly straight, the corners 4 on the cutters will not lie at the corners of the rectangular figure produced by the dotted lines 3. I, therefore, provide means 40 for adjusting the cutters to compensate for a bend in the rod 5. Each coupling member C is rigidly secured to a pair of cutters, and firmly secured at one of its ends to the rod 5. The yieldable ends of the split sleeves 45 E' firmly engage the rod 5, but the bore 16 (Fig. III) is larger in diameter than said rod. Each coupling member C is preferably reduced in thickness at 17 so that it may be bent to adjust the cutters with respect to 50 the rod 5. The means for bending the coupling member C comprises threaded members 18 screwed onto said coupling members, each of said threaded members being provided with an inturned annular flange 19 55 adapted to engage the rod 5. The axis of each threaded member 18 lies at an angle to the axis of rod 5, so that the threaded member may be rotated in one direction to force its annular flange 19 into engagement 60 with one side of rod 5, and it may be rotated in the opposite direction to engage the opposite side of the rod. When the threaded member 18 occupies the position shown in Fig. III, it engages the rod 5 at point X and the coupling member C is bent from

its normal position. A bend in the opposite direction may be reduced by screwing the member 18 to release annular flange 19 from the point X and to force said annular flange into engagement with the rod 5 at the point X'.

I claim:

1. A die having cutters, a split sleeve secured to one of said cutters, a connection device including a rod to which said split sleeve is slidably fitted, and a threaded member screwed onto said split sleeve, said threaded member having an inclined abutment face adapted to engage an end of said split sleeve to force it into engagement with said rod.

2. A die comprising cutters, connecting members uniting said cutters, one of said connecting members being yieldingly secured to another, and a screw threaded member surrounding and fitted to the last mentioned connecting member, said screw threaded member being operable to bend the yieldable connecting member.

3. A die comprising cutters, connecting members uniting said cutters, said connecting members including a rod and a tubular member surrounding said rod, and a cutter truing device screwed onto said tubular member and adapted to engage said rod, the axis of said cutter truing device being at an angle to said rod.

4. A die comprising cutters, connecting members uniting said cutters, said connecting members including a rod and a tubular member surrounding said rod, said tubular member being yieldingly secured to said rod, and a rotatable cutter truing device surrounding said rod and tubular member and screwed onto said tubular member, said cutter truing device having an inturned portion adapted to engage said rod and the axis of said cutter truing device being at an angle to the axis of said rod.

5. A die comprising cutters, connecting members uniting said cutters, said connecting members including a rod and a tubular member surrounding said rod, said tubular member being yieldingly secured to said rod, and a rotatable cutter truing device surrounding said rod and tubular member and screwed onto said tubular member, said cutter truing device having an inturned annular flange adapted to engage opposite sides of said rod and the axis of said cutter truing device being at an angle to the axis of said rod.

6. A die comprising two pairs of angular cutters arranged to cut envelop blanks, said cutters being provided with corners arranged to form the corners of a rectangular figure, a yieldable device connecting said two pairs of cutters, and a cutter truing device associated with and secured to said yieldable device, said cutter truing device being

operable to bend said yieldable device so as to vary the positions of the cutter corners which form the corners of the rectangular figure.

5 7. A die comprising angular cutters arranged to cut envelop blanks, said cutters being provided with corners adapted to form the corners of a rectangular figure, connecting members uniting said cutters, and a cutter truing device for truing said cutters to compensate for irregularities in said connecting device, said cutter truing device being secured to and movable independently of other elements of the die so as to position 10 the cutter corners at the corners of a true rectangular figure.

8. A die comprising angular cutters arranged to cut envelop blanks, said cutters

being provided with corners adapted to form the corners of a rectangular figure, a connecting device, adjustable fastening means for securing said cutters to said connecting device in different positions to provide for the cutting of envelop blanks of different dimensions, and a cutter truing device for 25 truing said cutters to compensate for irregularities in said connecting device, said cutter truing device being associated with and secured to the elements of the die so as to position the cutter corners at the corners of 30 a true rectangular figure.

CHARLES F. PFLANZE.
